CLAIM

The ornamental design for a pitcher, as shown.

DESCRIPTION

FIG. 1 is a perspective view of a pitcher illustrating our new design;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The broken lines represent portions of the structure that form no part of the claim.
